C. W. SCHWARTZ, JR.
PROCESS OF DRYING STOCKINGS ON FORMS.
APPLICATION FILED AUG. 7, 1919.

1,411,876.

Patented Apr. 4, 1922.

UNITED STATES PATENT OFFICE.

CHARLES W. SCHWARTZ, JR., OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

PROCESS OF DRYING STOCKINGS ON FORMS.

1,411,876.

Specification of Letters Patent.

Patented Apr. 4, 1922.

Application filed February 19, 1921. Serial No. 446,356.

To all whom it may concern:

Be it known that I, CHARLES W. SCHWARTZ, Jr., a citizen of the United States, residing in Philadelphia, Pennsylvania, have invented certain Improvements 5 in Processes of Drying Stockings on Forms, of which the following is a specification.

One object of my invention is to provide means for drying stockings on forms and at 10 the same time to prevent, to a certain degree, the shrinking of the stocking while on the form.

A further object of the invention is to provide means for holding the stocking on 15 the form by suction.

These objects I attain in the following manner, reference being had to the accompanying drawings, in which:

Fig. 1 is a side view of a stocking form, 20 showing a stocking in place and partially broken away;

Fig. 2 is a sectional view on the line 2—2, Fig. 1;

Fig. 3 is a sectional view on the line 3—3, 25 Fig. 1;

Fig. 4 is a sectional view on the line 4—4, Fig. 1;

Fig. 5 is a sectional view on the line 5—5, Fig. 1;

Fig. 6 is an exaggerated view, showing the stocking fabric drawn into the perforations of the form;

Fig. 7 is a view showing the perforations at one end only of the form; and

Fig. 8 is a diagrammatic sectional view 35 illustrating a form within a drying chamber.

In carrying out my invention, I provide a form such as described and claimed in an 40 application for patent filed by Walter M. Schwartz of even date herewith, serial No. 215,872. This form is made of metal and is hollow, as shown in the sectional view, having thin side members shaped to conform 45 to the shape of a stocking. These members are spaced apart and are connected by braces, or rivets, 2. The edges of the side sections are secured by rivets 3, although it will be understood that the form may be 50 made in any manner without departing from the essential features of my invention.

The lower end of the form is connected to a pipe 4 to which is attached a suction

pump; or fan, shown in diagram, as at 5. The form is perforated, as at 6. In some 55 instances, it may be perforated at the toe section, as at 7. In fact, in the form shown in Fig. 1, the perforations are arranged so as to be opposite the reinforced portion of the stocking, such as the foot portion and 60 the knee portion. In some instances, the form may be perforated throughout its length, or it may be perforated only at the bottom, as shown in Fig. 7, or at the open 65 end of the stocking.

In carrying out my invention, the air is sucked through the stocking and in this sucking operation the fabric of the stocking 70 a, Fig. 6, is drawn into the perforations 6, so that the tendency is to hold the stocking firmly on the form while being dried, materially reducing the shrinkage of the fabric. It is desirable, in many instances, to prevent shrinking at the foot. This can be accomplished in the same manner, as 75 the fabric will be drawn into the perforations at the foot in the same way, as shown in Fig. 6.

The form may be enclosed in a drying chamber 8, as shown in diagram, Fig. 8, 80 in which are steam pipes 9, or into which hot air may be introduced. Means may be provided for moving the stocking form into and out of this chamber. Any of the ordinary stocking drying machines may be used 85 without departing from the spirit of the invention.

While I have described my process particularly in connection with drying stockings, it may also be used in drying other 90 garments, which are liable to shrink in drying.

I claim—

The process herein described of preventing shrinking of knitted stockings and like 95 garments of relatively elongated tubular form while being dried, said process consisting in placing said garment on a form which is perforated near the open end of the garment, then causing air to be drawn into the 100 form and through the walls of the garment, causing the fabric of the garment to be drawn into the perforations thus preventing material shrinkage of the fabric while the garment is on the form.

CHARLES W. SCHWARTZ, JR.

Certificate of Correction.

It is hereby certified that in Letters Patent No. 1,411,876, granted April 4, 1922, upon the application of Charles W. Schwartz, Jr., of Philadelphia, Pennsylvania, for an improvement in "Processes of Drying Stockings on Forms," an error appears in the printed specification requiring correction as follows: In the heading to the printed specification, line 6, for the words "Application filed February 19, 1921. Serial No. 446,356." read *Application filed August 7, 1919. Serial No. 316,004.*; and that the said Letters Patent should be read with this correction therein that the same may conform to the record of the case in the Patent Office.

Signed and sealed this 9th day of May, A. D., 1922.

[SEAL.]

KARL FENNING,

Acting Commissioner of Patents.
